PROTECTIVE SYSTEM

Frank Pedatella, New Kensington, Pa.

Application October 10, 1935, Serial No. 44,467

7 Claims. (Cl. 175—294)

My invention relates to a system for indicating the condition of an electric circuit and for controlling the circuit under certain conditions. The system includes means for protecting the load devices in the circuit in the event that a circuit breaker which has been automatically opened by an overload current is closed while an overloading defect is still present in the circuit.

10 By my invention, I provide load-limiting means in the form of a circuit interrupter or overload switch for opening a circuit, upon the occurrence of a fault therein, and maintaining the circuit open until intentionally reclosed. The provision of such means obviates the necessity of using fuses in the circuit, and provides convenient means whereby the circuit can again be put in an operative condition in a convenient and positive manner. If the circuit is manually closed 15 while the fault therein is not cleared, the reclosing will operate a circuit in a control box and cause all the electric devices connected to the control box to cease to function.

I also provide means by the operation of which the current is entirely cut off momentarily from the control box and the electric circuits connected thereto. The operation of such means will restore the circuits in the control box to the normal setting.

30 The invention may be readily understood by reference to the accompanying drawing, illustrating diagrammatically an embodiment of my invention.

As shown in the drawing, an electrical load device 1 is adapted to be connected to a supply circuit 2 through the contacts of a manually operable circuit breaker or overload switch 3 and a control box 4. Any number of electrical load circuits may be connected to the said control box, for example, all the devices used on a single floor of a building. Each of the said devices has a circuit breaker, similar to circuit breaker 3, in series in the circuit, as illustrated by the device 5 and an associated overload switch 6. The devices 1 and 5, for example, may be of any character, such as industrial devices or the ordinary household appliances, lamps, motor-driven appliances or heating device. The manually operable circuit breaker or overload switch 3, consists of a snap-action switch which can be manually operated between closed and open positions and which, when operated, retains its position. In addition, the switch may be opened by the energization of a solenoid 7 acting on a core 8. Core 8 is attached to the operating mechanism of the

switch so that when the solenoid 7 is energized the circuit is opened. Once opened, the switch is closed by a manual operation.

The control box 4 has therein a main relay or circuit breaker 9 which is operated by a relatively low-resistance overload or tripping coil 10 acting on core 11 and by a relatively high-resistance closing coil 12 acting on core 13. One end of tripping coil 10 is connected to one of a pair of contacts 10a, and the other end to one of the supply circuit conductors leading from the control box to the load devices. One end of closing coil 12 is connected to one of a pair of contacts 12a, and the other end is connected through a lock-out relay or circuit breaker 14 to the other 10 of the supply circuit conductors leading from the control box to the load devices. Connected to cores 11 and 13 is a member 15 so adapted that when opening coil 10 is adequately energized, the contacts 12a are bridged and when closing coil 12 is energized contacts 10a are bridged. Contacts 10a when bridged complete the supply circuit. The lock-out relay 14 is connected in parallel with tripping coil 10 and contacts 10a, and when energized opens contacts 14a. A normally closed switch 16 is connected in the supply circuit. The function of this switch will be later described.

The drawing illustrates the conditions of the circuit so long as the devices which are in use are drawing only normal current from the supply circuit 2. The power current passes from one side of supply line 2, through contact 10a, coil 10, through the various devices, and thence to the other side of the supply circuit. The coil of the lock-out relay or circuit breaker 14 is normally subject only to the relatively small voltage drop through the overload or tripping coil 10 and is, therefore, not energized sufficiently to open its contacts so long as normal current is being consumed by the devices.

If an overload occurs, due to any defect in the device 1, for example, or in the circuit in which it is connected, the excessive current flow resulting will cause the overload switch 3 to move core 8 and open the defective circuit. The operation of the other devices, such as device 5, will not be affected. If the overload switch 3 is then manually operated to close the circuit while the defect remains, an overload current passes 50 through tripping coil 10, and acts upon core 11 to open contacts 10a. This removes the shunt from across the coil of lock-out relay 14 which is then subject to the full line voltage and operates to open its contacts 14a. The coil of lock-out 55

relay 14 remains energized and its contacts 14a open as long as any of the load circuits are closed. The contacts 12a are bridged immediately after the operation of lock-out relay 14, it being understood that the relay 14 operates immediately after the circuit breaker member 15 moves to open the contacts 10a and while such member 15 is still in the course of its movement to bridge the contacts 12a.

The current passing through the coil of lock-out relay 14, due to its resistance, is insufficient to operate the devices connected to control box 4 and the fact that these devices cease to operate will warn that there is a defect in some device connected to the circuit or in the circuit itself.

After the defect has been remedied, the normal circuit condition will be restored to the system by momentarily opening the switch 16, which is manually operated. The opening of the circuit at switch 16 will deenergize the lock-out relay 14 coil and will permit its contacts 14a to re-close. The closing coil 12 is thus connected directly across the supply circuit through the auxiliary contacts 12a. This attracts core 13 which opens auxiliary contacts 12a. Closing coil 12 is de-energized and then the contacts 10a are bridged. The circuit, through circuit breaker 9, is thus restored to normal operating condition. The load devices which are in normal operating condition will immediately begin to function, and the device in which the fault is present, either in the device itself or in its associated circuit, will not function. So, also, if the current to all the load devices is shut off, the cessation of current flow will cause the coil 14 to be deenergized, and as soon as current is again connected to any load device the normal circuit conditions in control box 4 will be restored.

The overload switches 3 and 6 are more sensitive to overload current than the main relay or circuit breaker 9. Thus, upon the occurrence of a defect in the circuit of a load device 1 or 5, the switch (3 or 6) in such circuit will operate before overload current adequate to operate the circuit breaker is reached. However, it will be manifest that if the switches 3 and 6 and circuit breaker 9 are equally sensitive, an overload in one load circuit will operate the circuit breaker 9 simultaneously with the switch (3 or 6) in such circuit. If the overloaded circuit is the only load circuit in service at the moment overload occurs, the coil of relay 14 will not be energized, and the contacts 14a will remain bridged, so that when the switch 16 (or the switch (3 or 6) of the sound or normal load circuit) is closed, the coil 12 of the circuit breaker will be energized, and the contacts 10a will be bridged for normal operation of all but the overloaded circuit in which the protective switch (3 or 6) stands in open position. If the latter switch be inadvertently closed the system will operate in the manner already described. If both load circuits are in service, when one of them is overloaded, and, as above mentioned, the switch of the overloaded circuit and the circuit breaker both move into emergency position, the relay 14 will open and remain open, due to the current flowing through the sound or unaffected load circuit. In such case the circuit breaker 9 may be returned to normal position across the contacts 10a, either while the switch in the defective circuit stands open, or after the defect in such circuit has been remedied, by momentarily opening the switch 16, or by opening and reclosing the sound load circuit.

It will be thus seen that by the use of my de-

vice the use of fuses to protect the system can be entirely eliminated, and, even though a defect occurs in one circuit, none of the load devices connected to the supply line through the control box will be injured by an overload or by an attempted closure of a circuit breaker or switch when a defect is still present in its associated circuit. The devices in which no fault is present will operate precisely as though all the circuits connected to the control box were in operating condition. My arrangement provides a safe, convenient, positive, and inexpensive arrangement for the protection of electrical devices from injuries due to overloads.

While I have shown and specifically described the present preferred embodiment of my invention, it will be understood that the invention may be otherwise constructed and embodied within the scope of the following claims.

I claim:

1. In apparatus for eliminating the customary use of fuses in an electric system including a plurality of load circuits connected to a supply source and each subject to the control of a manually operated switch, the combination of a circuit breaker for disconnecting all of said load circuits from said source, opening and closing coils for said circuit breaker, opening coils severally cooperating with said switches, whereby, when an overload condition occurs in any of said load circuits, the switch which normally is manually operated for the control of such circuit is automatically opened, the opening coil of said circuit breaker being responsive to current drawn from said source upon the manual reclosing of the automatically opened switch while overload condition still exists, and means operated by said current for preventing energizing of the closing coil of said circuit breaker.

2. In apparatus for eliminating the customary use of fuses in an electric system including a plurality of load circuits connected to a supply source and each subject to the control of a manually operated switch, the combination of a circuit breaker for disconnecting all of said load circuits from said source, opening and closing coils for said circuit breaker, opening coils severally cooperating with said switches, whereby, when an overload condition occurs in any of said load circuits, the switch which normally is manually operated for the control of such circuit is automatically opened, the opening coil of said circuit breaker being responsive to current drawn from said source upon the manual reclosing of the automatically opened switch while overload condition still exists, means operated by said current for preventing energizing of the closing coil of said circuit breaker, and manually operable means for rendering said last-mentioned means ineffective.

3. In apparatus for eliminating the customary use of fuses in an electric system including a plurality of load circuits connected to a supply source and each subject to the control of a manually operated switch, the combination of a circuit breaker for disconnecting all of said load circuits from said source, opening and closing coils for said circuit breaker, opening coils severally cooperating with said switches, whereby, when an overload condition occurs in any of said load circuits, the switch which normally is manually operated for the control of such circuit is automatically opened, the opening coil of said circuit breaker being connected in series

with the load and adapted to open the circuit breaker upon the manual reclosing of the automatically opened switch while overload condition still exists, and a lock-out relay in parallel with 5 said opening coil and adapted to be operatively energized substantially simultaneously therewith for preventing energizing of the closing coil of the circuit breaker.

4. In apparatus for eliminating the customary 10 use of fuses in an electric system including a plurality of load circuits connected to a supply source and each subject to the control of a manually operated switch, the combination of a circuit breaker for disconnecting all of said load 15 circuits from said source, opening coils severally cooperating with said switches, whereby, when an overload condition occurs in any of said load circuits, the switch which normally is manually operated for the control of such circuit is automatically opened, said circuit breaker having an 20 opening coil which is normally connected in series with the load and adapted to open the load circuit upon reclosing of the automatically opened switch while overload condition still exists, and 25 means for reclosing the circuit breaker.

5. In apparatus for eliminating the customary use of fuses in an electric system including a plurality of load circuits connected to a supply source and each subject to the control of a manually 30 operated switch, the combination of a circuit breaker for disconnecting all of said load circuits from said source, opening coils severally cooperating with said switches, whereby, when an overload condition occurs in any of said load circuits, 35 the switch which normally is manually operated for the control of such circuit is automatically opened, said circuit breaker having an opening coil which is normally connected in series with the load and adapted to open the load circuit upon reclosing of the automatically opened switch 40 while overload condition still exists, and a closing

coil for closing said circuit breaker when the current supply is interrupted.

6. In apparatus for eliminating the customary use of fuses in an electric system including a plurality of load circuits connected to a supply source and each subject to the control of a manually operated switch, the combination of a circuit breaker for disconnecting all of said load circuits from said source, opening coils severally 5 cooperating with said switches, whereby, when an overload condition occurs in any of said load circuits, the switch which normally is manually operated for the control of such circuit is automatically opened, said circuit breaker having an opening coil which is normally connected in series 10 with the load and adapted to open the load circuit upon reclosing of the automatically opened switch while overload condition still exists, and a closing coil for closing said circuit breaker when 15 the current supply is interrupted.

7. In apparatus for eliminating the customary use of fuses in an electric system including a plurality of load circuits connected to a supply source and severally subject to the control of manually operated switches, the combination of opening 20 coils severally cooperating with said switches, whereby, when an overload condition occurs in any of said load circuits, the switch which normally is manually operated for the control of said circuit is automatically opened, a circuit 25 breaker controlling connections between said load circuits and said source, said circuit breaker including an opening coil connected to open the circuit breaker upon the reclosing of the automatically opened load circuit while overload condition still exists, electric lock-out means adapted to be energized substantially simultaneously with the opening coil of said circuit breaker for preventing reclosing of the circuit breaker while overload remains in connection with said source. 30
